UNITED STATES PATENT OFFICE

JOSEPH BORZELLINO, OF ATLANTIC CITY, NEW JERSEY

DESIGN FOR A GAME BOARD

Application filed October 23, 1930. Serial No. 37,353. Term of patent 14 years.

To all whom it may concern:

Be it known that I, JOSEPH BORZELLINO, a citizen of the United States, residing at 2611 Arctic Avenue, Atlantic City, in the county of Atlantic, and State of New Jersey, have invented a new, original, and ornamental Design for a Game Board, of which the following is a specification, reference being had to the accompanying drawing, forming part thereof.

Fig. 1 is a plan view of a game board showing my new design, and Fig. 2 is a side elevation of same.

I claim:

The ornamental design for a game board as shown.

JOSEPH BORZELLINO.
